TABLE FOR ROLLING MILLS

Ernest Drexler, Pittsburgh, Pa.

Application November 5, 1934, Serial No. 751,502

3 Claims. (Cl. 80—47)

My invention relates to tables for rolling mills in which there are used entry or delivery tables for the purpose of reversing the direction of travel of the material to re-enter the same between the working rolls of the mill when it is desired, for example, to further reduce the thickness of the material, or to obtain a smoother finish or greater hardness thereof.

A rolling mill table usually comprises a series of rollers driven either by miter gears and line shafts, worms and worm wheels, chains and sprockets, cranks and connecting rods, or by individual coupled motors.

Whenever a change in the direction of travel of the material is desired, the direction of rotation of the roller driving means must be reversed. This requires time, and if frequent reversals are effected, the output of the mill is of course considerably diminished. Moreover, there is the inherent disadvantage of the table mechanism being subjected to stresses and strains and excessive wear due to the starting, stopping and reversing of the direction of rotation of the rollers. Especially is this true in respect to the reversible electric motors and related gear reduction units which comprise the most common means of driving the rollers. Motors of special and expensive construction are required to withstand frequent reversals without overheating. Furthermore, the common practice heretofore has been to pivot the tables at their ends remote from the rolls and to tilt the ends of the tables nearer the rolls upwardly so that reversal of the direction of rotation of the rolls is effective to convey the material over the rolls for re-entry between the same. This, however, has the disadvantage, especially in the case of the rolling of light weight, smooth surfaced materials, that considerable slippage between the material and the conveyor rollers occurs, the material, due to insufficient traction and under the influence of gravity tending to slide down the inclined table away from the mill rolls instead of being conveyed over the same. Consequently, the services of an attendant stationed at the table to push the material upwardly over the table are required.

The general object of the present invention is to provide a relatively simple, thoroughly practical table for use in rolling mills embodying a construction and mode of operation whereby the foregoing and other disadvantages inherent in present rolling mill tables are eliminated.

The novel features of construction, combination and arrangement of parts in accordance with my invention will now be more fully described with reference to the accompanying drawings, in which Fig. 1 is a top plan view of a rolling mill equipped with tables embodying the invention, Fig. 2 a side elevation of the mechanism illustrated in Fig. 1, showing one of the tables in longitudinal section,

Fig. 3 an end elevation of the mechanism shown in Figs. 1 and 2, Fig. 4 an enlarged transverse section through one of the tables showing the vertically movable set of rollers in an elevated position, Fig. 5 an enlarged horizontal section taken approximately on the line 5—5 of Fig. 2, Fig. 6 a detail sectional view through the clutch device for effecting elevation and permitting lowering of the movable sets of rollers of the tables, Fig. 7 a top plan view illustrating chain conveyor elements which may be used in lieu of the rollers illustrated in Figs. 1 to 5, and Fig. 8 a side elevation of the structure illustrated in Fig. 7 and showing by dotted lines the vertically movable chain conveyor in elevated position.

In the drawings, A designates, generally, the usual housing of a sheet or plate hot mill having journaled therein the usual superimposed rolls a, a. As shown, separate conveyor tables constructed in accordance with the invention and generally designated as B, B₁, are disposed, one at the entering side and the other at the delivery side of the rolls, for respectively conveying the material to and from the rolls. This is a preferred arrangement inasmuch as the tables thus arranged are adapted for cooperation with each other to effect repeated passes of the material between the rolls. However, the two tables are entirely separate and distinct from each other, and either may be used to the exclusion of the other. Each table comprises a frame or carriage 10 provided with grooved supporting wheels 11 (Fig. 4) resting on track rails 12 of inverted V-shaped section whereby the carriage 10 is supported and guided for movement bodily towards and away from the rolls a.

The carriage 10 is composed of a pair of side rails 13 connected together by transverse members 14 and constitutes a carrier for a set of transverse rollers 15, suitably journaled at their ends in said side rails. All the rollers 15 are of the same diameter and, as shown, are disposed in a common horizontal plane to properly support and convey the material resting thereon. They are driven in unison in any suitable or desired manner, as, for example, by means of an electric motor individual to each roller and contained therein as shown for instance in my Patent No. 1,889,174 and as indicated by dotted lines in Figure 4 of the drawings. During operation of the table the carriage 10 must be held against movement along the track rails 12. As illustrated in Fig. 4, a simple yet effective means of accomplishing this purpose comprises clamp bolts 16 depending from the axle 17 of a pair of the wheels 11 or from one of the cross members for clamping engagement with portions of the track rails 12.

In addition to the carriage 10 supporting the rollers 15, the table includes a vertically movable frame 18 (Fig. 4), comprising a pair of side

rails 19 connected together by cross members 20 and carrying, like the carriage 10, a set of transverse rollers 21. The side rails 19 of said frame 18 are disposed outwardly of the side rails 13 of the carriage 10 and have the ends of the rollers 21 journaled therein.

Like the rollers 15 of the carriage 10, the rollers 21 of the frame 18 are all of the same diameter and are driven in any suitable manner, as, for example, by means of individual motors mounted therein.

The rollers 15 of carriage 10 all rotate in a direction to advance the material disposed thereon toward the rolls *a*, while the rollers 21 of the frame 18 all rotate in the opposite direction. During the normal operation of the mill the rollers 21 are disposed suitably below the rollers 15 so that the material rests upon and is moved only by the rollers 15. When it is desired to reverse the direction of travel of the material, the frame 18 is raised vertically so as to dispose the rollers 21 above the rollers 15 parallel thereto, in which case the material will be moved by the rollers 21.

The means mounting the frame 18 for vertical movement comprises a base 22 suitably mounted in a fixed position below the track rails 12 of carriage 10 and having suitably guided therein for vertical movement a carrier 23 which is forked at its upper end to provide arms 24, (Figs. 4 and 5), to which the side rails 19 of frame 18 are detachably connected as shown at 25 in Fig. 4. The carrier 23 is provided with a rack 26 with which meshes a pinion 27 (Figs. 3 and 5), fixed to a horizontal shaft 28 journaled in the base 22. Thus, by the rotation of the shaft 28 in one direction the carrier 23, and with it the frame 18, are vertically elevated. On the other hand, whenever free rotation of the shaft 28 is permitted, due to the weight of the carrier 23 and the frame 18, said carrier and frame gravitate to their normal lowermost position in which the rollers 21 are disposed below the rollers 15. The side rails 13 of the carriage 10 are provided with recesses opening through their upper edges to accommodate the preferably reduced ends of the rollers 21 and the cross members 20 thereby to permit said rollers 21 to move downwardly below the rollers 15.

From the foregoing description, the general mode of operation of the tables B, B' will be apparent. Normally, the rollers 21 of both tables are disposed below their related rollers 15, only the latter rollers being effective to support and move the material and the said rollers 15 of both tables B, B' rotating in the same direction whereby the material is advanced toward the rolls *a* by the rollers 15 of the table B at the entrance side of the rolls *a* and is carried away from the rolls *a* by the rollers 15 of the table B' at the delivery side of the rolls. Now, if it is desired to return the rolled material from the table B' to the table B to again be passed between the rolls *a*, the frames 18 of the respective tables are raised vertically to dispose their rollers 21 above the rollers 15. The material is thus picked up and elevated by the rollers 21, and the direction of rotation of the rollers 21 being counter to the direction of the rollers 15, the elevated material is moved by the rollers 21 of the table B' toward the rolls *a*. The amount of elevation of the rollers 21 is such that the material may pass over the rolls *a* onto the rollers 21 of the table B, and, thereupon, the frames 18 of the respective tables are lowered to deposit the material on the rollers 15 of the table B, whereby the sheet again is ad-

vanced by the latter rollers to and between the rolls *a*. Different types of mills may require different amounts of elevation of the rollers 21, but the present manner of mounting the rollers 21 obviously provides for obtaining any desired amount of elevation of said rollers within practicable limits.

Side guards 29 are provided to guide the material in its movement over the tables, and a feature of the invention resides in so mounting said side guards that they not only are adjustable to accommodate therebetween material of different widths, but are effective to guide the material whether the same is resting on the rollers 15 or on the elevated rollers 21.

The side guards 29, (Fig. 4), are in the form of longitudinally extending plates disposed, one at each side of the frame 18 and mounted, respectively, on the inner ends 30 of levers 31 which are pivoted intermediately in brackets 32 carried by the side rails 19 of frame 18. The other or outer ends 33 of said levers extend downwardly and outwardly and are connected together by a link or rod 34. Thus, by longitudinal movement of the respective rods 34 the levers 31 are swingable in unison to move the guards 29 either inwardly or outwardly. Any suitable means may be provided to hold the guards in a desired adjusted position. Such means, as here shown, comprise a bracket 35 for each link or rod 34 fixed to the related side rail 19 of frame 18 and have the related link or rod slidably engaged therewith, the bracket having an opening for alignment with any one of a number of openings in the link or rod for the reception of a suitable pin or keeper 36.

Special and novel means are provided for elevating and permitting lowering of the frames 18 of the tables B, B' in unison. On corresponding ends of the shafts 28 are fixed bevel gears 37 (Fig. 41), which mesh with similar gears 38 fixed on a shaft 39. The pairs of gears 37, 38, are disposed preferably within suitable housings 40 in which the shaft 39 is journaled. Alined with shaft 39 is a shaft 41 having fixed thereto a worm wheel 42 with which meshes a worm 43 on the shaft of a driving motor 44. Adjacent ends of the shafts 39 and 41 have fixed thereto bevel gears 45 and 46, respectively, which mesh with other bevel gears 47 journaled in a housing 48 mounted for rotation about the common axis of the shafts 39, 41. The gears 45, 46 and 47, together with the housing 48, obviously constitute a differential gear connection between the shafts 39, 41 operable either to transmit power from the shaft 41 to shaft 39 for the purpose of rotating the shafts 28 to raise the frames 18, or to permit the shafts 28, 39 to rotate under the influence of the weight of the frames 18 and their carriers 23, thereby permitting said frames and carriers to gravitate to their lowermost positions with the rollers 21 disposed below the rollers 15 while the motor 44 continues to operate and drives the shaft 41 in a single direction. In other words, continuous rotation of the motor and consequent continuous rotation of the shaft 41 being assumed, it is manifest that if the differential gear housing 48 is held against rotation, the gear 46 will drive the gears 47 and the latter gears will drive the gear 45, thereby imparting rotation to the shaft 39 and the shafts 28. It is understood, of course, that the direction of rotation of the motor 44 is such as to rotate the shafts 28 in a direction to elevate the frames 18. Now, on the other hand, when the gear housing 48 is not held against rotation,

it is apparent that the gears 47 may rotate with the housing about the gear 45 without imparting motion to the shaft 39, so that when the frames are in an elevated position and the housing 48 is not held against rotation, shaft 39 is free to turn to permit the frames to gravitate to their lowermost positions, despite continued rotation of the shaft 48 by the motor.

A practical means of releasably holding the gear housing 48 against rotation is illustrated in Figures 1, 3 and 6 of the drawings and comprises a pair of arms 49 pivoted to a suitable fixed support 50 for swinging movement toward and away from the housing and carrying brake elements 51 for engagement with the housing. A bell-crank lever 52 is pivoted to the free end of one of the arms 49 and is connected at one end to the free end of the other of the arms 49 by a link 53 and at its other end is connected by a link 54 with an intermediate portion of a pivoted lever 55 having connected therewith a solenoid core 56 operating within a solenoid winding 57. The lever 55 is weighted and is so disposed as to normally operate through its connection with the arms 49 to urge them inwardly to braking positions relative to the housing 48. On the other hand, the solenoid comprising the core 56 and the winding 57 is so disposed as to swing the lever 55 in a direction to move the arms outwardly into non-braking relationship to the housing 48 when the winding 57 is energized. As illustrated in Fig. 6 of the drawings, a foot operable switch 58 may be provided in the solenoid circuit for opening and closing the circuit to respectively release and hold the housing 48. Because of this arrangement it is clear, that simply by the opening of the solenoid circuit the frames 18 will be elevated and by the closing of said circuit the frames are permitted to gravitate to their lowered positions, while the motor 44 continues to operate in a single direction. Thus, provision obviously is made for quickly returning any material from the table B' to the table B for re-entry between the rolls *a* without reversing the direction of rotation of any of the rollers 15 or 21.

As has been said, the rollers 15 and 21 preferably are driven by individual electric motors, and for providing current of desired frequency for operating said motors, a generator 59 preferably is belted or otherwise suitably connected with the motor 44 to be driven thereby.

As shown in Fig. 2 of the drawings, bumper springs 60 or suitable equivalents thereof, such as pneumatic devices, preferably are provided to cushion the carriers 23 for the frames 18 at the ends of the up and down movements of said carriers.

Due to the detachable connections 25 between the frames 18 and their carriers 23 said frames may at any time be disconnected from said carriers to be deposited on the carriage 10 for transportation by the latter along the track rails 12 either to clear the mill, or for any other desired purpose.

While rollers preferably are employed as supporting and conveying means for the material, the use of rollers for this purpose obviously is not essential. On the contrary, any equivalents of the rollers 15 and 21 may be employed. For example, from Figs. 7 and 8 of the drawings, it will be observed that the supporting and conveying means

for the material may comprise endless chains 61 operating over sprocket wheels 62 at the ends of the carriage 10' and the frame 18', respectively. For driving the chains 62 of the supporting and conveying means 10' the sprocket wheels at one end of said carriage 10' may be carried by a hollow member 63 equipped in the same manner as the rollers 15 and 21 with a motor for rotating the same. Similarly, for driving the chains of the frame 18' the sprocket wheels at one end of said frame may be carried by another hollow member 63 equipped with a motor for rotating the same.

While specific structural embodiments of the invention have been illustrated and described, the invention is readily capable of embodiment in other mechanical structures without a departure from its spirit and scope.

I claim:

1. A table for rolling mills comprising a wheeled carriage inclusive of spaced side rails, track rails on which said carriage is mounted for movement, means for securing said carriage against movement along said track rails, a series of material supporting and conveying rollers mounted on and extending transversely between the carriage side rails, means for driving all of said rollers in the same direction, a frame inclusive of side rails disposed outwardly of the carriage side rails, a series of material supporting and conveying rollers mounted on and extending transversely between the frame side rails, means for driving all of the rollers of the second series in a direction opposite to the rollers of the first series, means whereby the frame rollers are permitted to move downwardly below the carriage rollers, a support, vertically movable frame lifting means mounted in said support, and a detachable connection between said frame lifting means and said frame whereby the frame and its rollers may be deposited on the carriage for movement therewith.

2. A table for rolling mills comprising a horizontally movable carriage, material supporting and conveying means mounted thereon, a vertically movable support, material supporting and conveying means mounted on said support for vertical movement with said support above and below the first mentioned conveying means, means for vertically moving said support, and a detachable connection between said support and the moving means therefor whereby the support and its rollers may be deposited on the carriage for movement therewith.

3. A table for rolling mills comprising a material supporting and conveying element inclusive of a plurality of rollers having individual driving motors, a second material supporting and conveying element inclusive of a plurality of rollers having individual driving motors, a continuously operating motor, a connection between said motor and one of said elements whereby the motor may be made effective to elevate said element to a position with its rollers disposed above the rollers of the other element and whereby, during continuous operation of said motor, the elevated element may be lowered to a position with its rollers disposed below the rollers of the other element, and a generator driven by said motor for furnishing current to the individual driving motors of said rollers.

ERNEST DREXLER.
